UNITED STATES PATENT OFFICE.

GILBERT W. WARREN, OF ILION, NEW YORK, ASSIGNOR TO DAISY
MANUFACTURING COMPANY, OF PLYMOUTH, MICHIGAN, A COR-
PORATION.

AIR-GUN.

No. 830,121.

Specification of Letters Patent.

Patented Sept. 4, 1906.

Application filed November 4, 1903. Serial No. 179,770.

To all whom it may concern:

Be it known that I, GILBERT W. WARREN, a citizen of the United States, residing at Ilion, in the county of Herkimer and State of New York, have invented certain new and useful Improvements in Air-Guns, of which the following is a specification, reference being had therein to the accompanying drawings.

10 My invention relates to an improvement in what is commonly known as an "air-gun;" and it consists in the mechanism hereinafter pointed out and claimed.

15 The purpose of my invention is to provide a stop within the false barrel and which in this instance consists in a tubular piece of metal slotted or opened in the direction of its length, which is inserted within the false barrel and held stationary by any well-known 20 means, and also to provide an opening through the breech-plug from the magazine into the rear of the true barrel, so that as each shot is fired the remaining shot in the magazine are kept in position to be fed into 25 the true barrel after any particular shot may have been discharged from the gun.

In the drawings, Figure 1 is a vertical longitudinal section of my air-gun, portions of the working parts being shown in full lines 30 and portions in sectional lines, broken lines indicating parts removed. Fig. 2 is a vertical central section of the plug and adjacent parts of my air-gun, broken lines indicating parts removed. Fig. 3 represents a perspective view of the breech-plug, broken lines indicating parts removed. Fig. 4 is a perspective view of a tubular stop, slotted in the direction of its length. Fig. 5 is a perspective view of the piston-guide and spring-abutment, and Fig. 6 is a perspective view of the trigger.

Having described my invention with reference to the figures illustrated in the drawings, I will now proceed to describe the same more 45 in detail, in which description similar numerals of reference refer to corresponding parts in the several views.

In constructing my air-gun I provide a true barrel 1, which is supported at its base or 50 rear at 2 in the magazine breech-plug 3. The rear of the barrel may be mounted in the magazine breech-plug by screw-threading the parts or by crimping, swaging, or other suitable manner reducing the size of the rear

end of the barrel in order to swage the shot as 55 it is forced through that portion of the true barrel. The rear of the barrel is thus firmly held in the magazine breech-plug. The magazine breech-plug, with the barrel secured therein as heretofore pointed out, is 60 inserted within the false barrel or magazine 4, so that the front end 5 of the barrel flushes with the screw-threaded magazine-cap 6. The magazine-cap 6 is provided with an overlapping flange 7 and is provided with screw- 65 threads which engage the inner screw-threaded surface of magazine 4, the barrel passing into opening 8 in the screw-threaded cap, so that by removing screw- 70 threaded cap 6 the shot may be turned into 70 the magazine, and by replacing it the magazine is closed and the gun is ready to be loaded. For permanently locating the magazine breech-plug 3 I insert tubular stop 9, slotted at 10 in the direction of its length and 75 which is inserted in the outer or false barrel or magazine and suitably secured to the inner surface of the magazine or false barrel. I accomplish this, preferably, by tinning its outer surface, so that when it is in place and 80 heat is applied to the parts they become soldered together. It then acts as a stop against which the magazine breech-plug is held within the magazine or false barrel as an 85 abutment in the operation of the piston.

Magazine breech-plug 3, carrying barrel 1, is inserted in the magazine at the rear of the slotted tubular stop, the front edge of the magazine breech-plug resting against the edge of the stationary tubular stop and rear- 90 wardly of the same, where it may be suitably secured. For permitting the shot within the magazine to be fed into the true barrel I provide a passage-way through the breech-plug, which in this instance consists of horizontal 95 opening 12, intersecting cross-opening 14, so that a single shot may enter opening 12 and drop through opening 14 to the rear end of the true barrel in place for projection. The opening 13 is incidentally formed in the convenient cutting of space 14. The tubular magazine 4 is of the same diameter from end to end and is constructed ordinarily of metal tubing.

For operating upon each successive shot as 105 it passes into space 14 and discharging the same I provide a movable tubular piston or plunger 15, which is sufficiently small to pass

into the bore of the true barrel 1 when driven forward. At the rear end of the magazine breech-plug I bore or tap a hole 16 of sufficient diameter to freely admit piston 15, which can be driven through opening 16 into the bore of the barrel mounted in the magazine breech-plug. The piston 15 is provided with opening or slot 17 through its wall, Fig. 1, which permits the compressed air from the air-chamber 18 to pass through this opening and through the tubular piston 15 and against the shot at 14 and project it from the true barrel 1, following the shot and exercising its elastic influence upon it until it leaves the bore of the barrel.

The air-chamber 18 is formed by the wall of the false barrel and the magazine breech-plug at its front and at the rear by the piston-head 19, which is packed with oiled wicking or other suitable material for making the same air-tight, the piston-head being provided with a peripheral groove for supporting the wicking or other packing. Attached to the piston-head 19 I provide piston-rod 20, which extends rearwardly and terminates in hook or curve 21, the tip of which, 22, engages with catch 23 on trigger 24, pivoted in the frame at 25 and held in its position by coil-spring 26, one end of which bears on the trigger, the other end resting in a pocket in the frame.

At 27 I show a coil-spring suitably supported, one end of which bears against piston-head 19, which is movable, the other end bearing against abutment 28. The spring is put under compression by drawing back the piston-head 19, as hereinafter shown. Abutment 28 is formed substantially as shown, Fig. 5, having a groove 29 in the squared end for the reciprocal play of rod 20 and having longitudinal slot 30 for like play of hook 21 of that rod and holding the same in its proper position with the curved end downward, so as to be engaged by the catch 23 on the trigger when the gun is being charged. For compressing coil-spring 27 I provide in this instance a wire pull or link 31, which is held by

pin 32 passing through the stock, the other end being engaged by the curved end 21 of rod 20 when the gun has been discharged and is broken down for recharging, the link thus drawing rod 20 back, compressing spring 27, and bringing tip 22 of rod 20 into engagement with catch 23 on the trigger.

Changes and modifications in the construction of my air-gun may be made by one skilled in the art without departing from the spirit of my invention. In the description I have pointed out one of the ways in which I have practiced my invention and the one which I consider best.

What I claim as new, and desire to secure by Letters Patent, is—

1. In an air-gun having a magazine between the walls of a false barrel and a true barrel and having a removable cap at the outer end and a removable plug at the inner end, the combination, of means for removably fixing the said plug and abutting the same, said means consisting of a tubular member slotted through its length, adapted to be compressed to be slipped into place and coated with a material whereby, through the application of heat to the parts it may become soldered in place to hold the plug and likewise loosened for the removal of the said plug, substantially as shown.

2. In an air-gun, a removable breech-plug, and a slotted spring-sleeve having its outer surface prepared to be secured by the application of heat adjacent the plug to hold the same in place and removable to permit withdrawal of the plug, substantially as shown.

3. In an air-gun, a removable breech-plug, and a slotted spring-sleeve having its outer surface prepared to be secured by the application of heat adjacent the plug to hold the same in place, substantially as shown.

In testimony whereof I affix my signature in presence of two witnesses.

GILBERT W. WARREN.
